UNITED STATES PATENT OFFICE.

GEORGE A. MILLAR, OF RIDGEFIELD PARK, NEW JERSEY, ASSIGNOR TO COOPER HEWITT ELECTRIC COMPANY, OF HOBOKEN, NEW JERSEY, A CORPORATION OF NEW JERSEY.

GLASSWORKING MACHINERY.

Application filed January 1, 1927. Serial No. 158,432.

My present invention relates to glass working machinery and particularly to machinery for applying a rotating flame to glass to be worked.

5 Various objects and advantages of the invention will be obvious from the following particular description of forms of apparatus embodying the invention or from an inspection of the accompanying drawings; 10 and the invention also consists in certain new and useful features of construction and combinations of parts hereinafter set forth and claimed.

In the accompanying drawings there is 15 shown for purposes of illustration one form of apparatus embodying the invention, in which

Fig. 1 is a front elevation view,

Fig. 2 is a side elevation view and

20 Fig. 3 is a vertical mid section view looking from the front.

In the drawings the table 1 carries the fixed hollow cylinder 3 whose central opening registers with the opening 5 through 25 said table. Extending through the bore of said cylinder 3 is the cylinder 6 which is rotatable and slidable longitudinally therein. Said cylinder 6 has formed at its upper end the annular flange 8 having an annular 30 channel 10 formed in the lower surfaces thereof. About said cylinder 6 and having its upper surface bearing against the lower surface of said flange 8 is the collar 12 which is held in position by the springs 14, 14 bearing against the lower surface of said collar 35 at their lower ends and at the upper ends bearing against said cylinder 3, pins or rods 16, 16 are threaded into the lower surface of said collar 12 and extend one through 40 each of said springs 14, 14 and into a corresponding hole 18, 18 extending downwardly from the upper surface of said cylinder 3 to such a distance as to permit considerable longitudinal movement of said cylinder 6 45 in the bore of said cylinder 3. These pins 16, 16 serve to hold said springs 14, 14 in position and also to prevent rotation of said collar 12 when said cylinder 6 is rotated. In the lower surface of said collar 12 and in 50 the upper surface of said flange 8 are provided registering annular channels 20 and 22 respectively. An opening 24 formed through said collar 12 at one end connects with said channel 22 and at its opposite end 55 connects with the flexible hose 26 which

through the valve 28 connects to a suitable source of heating gas not shown. A foot treadle 30 and connecting rod 32 serve to open said valve 28 against the tension of a closing spring 34. A pair of openings 36, 36 60 each through said flange 8 connects at its inner end with said channel 20 and at its outer end with the gas pipe 38 which carries a gas jet 40 directed inwardly toward the center of rotation of said cylinder 6. 65

Near the lower end of said cylinder 6 which extends through and below said table 1 is provided a pulley 42 over which passes the belt 44 driven by the motor 46 whose starting and stopping and whose speed can 70 be regulated by a foot or hand control not shown. Said pulley 42 is keyed to said cylinder 6 through a sliding keyway 48 formed in said cylinder 6 and the bracket 50 supports said pulley 42 and permits the movement of said cylinder 6 along its axis through said pulley 42. At its lower end said cylinder 6 carries an annular flange 52 having an annular channel 54 formed in the lateral surface thereof. The fork member 56 pivoted to the table 1 by the bracket 58 carries a pair of dogs 60, which extend into said channel 54 at diametrically opposite points. A foot treadle (not shown) connected to said member 56 and operating against a tension spring serves to actuate said member 56 to raise said cylinder 6 longitudinally through said cylinder 3. 80

A bracket 70 under said table 1 carries the support member 72 which extends upwardly through the central opening 74 in said cylinder 6 and terminates above said flange 8 in the uppermost position thereof and below the converging point of flames from said gas jets 40, 40. At its upper end said support 72 carries a pair of fork members 76 and 78. On said member 76 is pivotally mounted the V block 80 and on said member 78 and opposite said block 80 is pivotally mounted the V block 82 on the pin 84, which is slidable in said member 76 and which carries on its outer end the handle member 86. A spring 88 mounted about pin 84 between block 80 and said member 76 serves to move said block 80 toward said block 82 for clamping a piece of work therebetween. In the drawings is illustrated a mercury switch having a glass envelope 90 positioned between said V blocks 80 and 82 and having a tubulation 92 extending from 100 105 110

the upper surface thereof. A gauge 94 in the form of a hook pivoted at one end to the cross bar of said fork member 76 and 78 and having the turned over end 96 extending inwardly toward said blocks 80, 82 serves to position said switch and tubulation between said blocks 80 and 82 in predetermined relation to the point of convergence of the flames from said jets 40, 40. A rod 98 connected 10 to said hook or gauge 94 at its pivot serves through the handle portion 100 to move said member 96 into and out of gauging position with respect to a switch body between said blocks 80, 82. In the use and operation of 15 the embodiment of the invention herein illustrated and above described, a piece of glassware having a tubulation thereon is mounted between said blocks 80, 82 with the tubulation thereof positioned at or along the 20 axis of rotation of said cylinder 6, said gauge 94 being used to determine the position. Gas being admitted to said jets 40, 40 and lit thereat, the fires are set in rotation by means of said motor 46. Said foot 25 treadle connected to member 56 is used to cause the raising and lowering of the flames of said jets 40, 40 to bring them to desired position against said tubulation to cause the melting of the glass thereat, upon which the 30 tubulation may be drawn away and the glass envelope sealed off without the tubulation. In the raising and lowering of said cylinder 6 and the attached parts through said foot treadle and its said spring (not shown) said 35 annular flange 52 serves as a stop against said bracket 50 for limiting the upward movement of said cylinder 6 and the attached parts.

It is to be understood that the present invention can be applied in machines and apparatus for handling glassware other than that used to illustrate the invention and for performing operations other than those described for purposes of illustration and example. The invention is not limited to machines which have parts rotatable upon vertical axes, nor because the gases of rotation and of the rotatable parts can be inclined or can be horizontal as in a lathe type of 50 machine.

And the invention can be applied for different kinds of machinery for blowing or other working of glass.

While I have shown and described and 55 have pointed out in the annexed claims certain novel features of the invention, it will be understood that various omissions, substitutions and changes in the forms and details of the device illustrated and in its 60 operation may be made by those skilled in the art without departing from the spirit of the invention.

I claim—

1. In a glass working machine, in combination, a member mounted to be rotatable

about and slidable along a given axis, a second member having a face against a face of said rotatable member, means for holding said second member against rotation with said rotatable member and for holding said faces in predetermined relation, one of said members having an arcuate channel between said registering faces and each of said members having an opening therethrough registering with said channel, a gas jet mounted 70 to said rotatable member and connecting with the opening therethrough and a work holder in operable relation to said gas jet.

2. In a glass working machine, in combination, a member mounted to be rotatable 80 about and slidable along a given axis, a second member having a face against the face of said rotatable member, means for holding said second member against rotation with said rotatable member and for holding said faces in predetermined relation, one of said members having an arcuate channel between said registering faces and each of said members having an opening 85 therethrough registering with said channel, a gas jet mounted to said rotatable member and connecting with the opening therethrough and discharging inwardly toward the center of rotation of said rotatable member, and a work holder in operable relation 90 to said gas jet.

3. In a glass working machine, in combination, a member mounted to be rotatable about and slidable along a given axis, a second member having a face against the 100 face of said rotatable member, means for holding said second member against rotation with said rotatable member and for holding said faces in predetermined relation, one of said members having an arcuate channel between said registering faces and each of said members having an opening 105 therethrough registering with said channel, a gas jet mounted to said rotatable member and connecting with the opening therethrough and a work holder in operable relation to said gas jet, and means for rotating said rotatable member at will and for moving it longitudinally at will in either 110 direction.

4. In a glass working machine in combination, a guideway, a hollow cylinder rotatable in said guideway and movable longitudinally therewith, means for holding said collar against rotation and for holding it in predetermined longitudinal relation to said cylinder, the adjacent faces of said collar and said cylinder having sliding contact with each other, one of said members having an annular channel extending between said adjacent faces and each of said members having an opening therethrough extending from the outside and registering with said channel, a tube connecting with the opening 120 in said collar and permitting movement of 125

said collar longitudinally with said cylinder, a gas jet carried by said cylinder and connected to the opening therethrough and a work holder in operable relation to said gas jet.

5. In a glass working machine, in combination, a guideway, a hollow cylinder rotatable in said guideway and movable longitudinally therein, a collar about said cylinder and movable longitudinally therewith, means for holding said collar against rotation and for holding it in predetermined longitudinal relation to said cylinder, the adjacent faces of said collar and said cylinder having sliding contact with each other, one of said members having an annular channel extending between said adjacent faces and each of said members having an opening therethrough extending

20 from the outside and registering with said channel, a tube connecting with the opening in said collar and permitting movement of said collar longitudinally with said cylinder, a gas jet carried by said cylinder and connected to the opening therethrough and projecting inwardly toward the center of rotation of said cylinder and a work holder in operable relation to said gas jet.

6. In a glass working machine in combination, a guideway, a hollow cylinder rotatable in said guideway and movable longitudinally therein, a collar about said cylinder and movable longitudinally therewith, means for holding said collar against rotation and for holding it in predetermined longitudinal relation to said cylinder, the adjacent spaces of said collar and said cylinder having sliding contact with each other, one of said members having an annular channel extending between said adjacent faces and each of said members having an opening therethrough extending from the outside and registering with said channel, a tube connecting with the opening in said

45 collar and permitting movement of said collar longitudinally with said cylinder, a gas jet carried by said cylinder and connected to the opening therethrough and a work holder in operable relation to said gas jet, means for the application of power to rotate said cylinder about its axis and to slide it along its axis, and a support for said work holder extending longitudinally through said hollow cylinder.

7. In a glass working machine, in combination, a guideway, a hollow cylinder rotatable in said guideway and movable longitudinally therein, a collar about said cylinder and movable longitudinally therewith, means for holding said collar against rotation and for holding it in predetermined longitudinal relation to said cylinder, the adjacent faces of said collar and said cylinder having sliding contact with each other, one of said members having an annular channel extending between said adjacent faces and each of said members having an opening therethrough extending from the outside and registering with said channel, a tube connecting with the opening in said 60 collar and permitting movement of said collar longitudinally with said cylinder, a gas jet carried by said cylinder and connected to the opening therethrough and projecting inwardly toward the center of rotation of said cylinder and a work holder in operable relation to said gas jet, means for the application of power to rotate said cylinder about its axis and to slide it along its axis, and a support for said work holder extending longitudinally through said hollow cylinder.

8. Signed at Hoboken, in the county of Hudson and State of New Jersey, this 31st day of December A. D. 1926.

GEORGE A. MILLAR.
